DESIGN FOR A SMOKING PIPE

Charles W. Von Rosenberg, Kansas City, Mo.

Application June 6, 1945, Serial No. 119,927

Term of patent 14 years

(Cl. D85—8)

To all whom it may concern:

Be it known that I, Charles W. Von Rosenberg, a citizen of the United States, residing at Kansas City, county of Jackson, State of Missouri, have invented a new, original, and ornamental Design for a Smoking Pipe, of which the following is a specification, reference being had to the accompanying drawing forming a part thereof.

In the drawing:

I claim:

The ornamental design for a smoking pipe, as shown.

CHAS. W. VON ROSENBERG.
